REFRIGERATOR SHELF

Walter F. Schulz, Youngstown, Ohio, assignor to
 Truscon Steel Company, Youngstown, Ohio, a
 corporation of Michigan

Application October 29, 1935, Serial No. 47,301

3 Claims. (Cl. 211—143)

The present invention relates to sliding shelves, such as are commonly used in refrigerators, or other cabinet structures, and more particularly to supports for such shelves when in their extended or projected positions.

An object of the invention is to provide a novel and effective supporting means for the shelf which will be extended when the shelf is slid out from the cabinet, and which will support the shelf in advance of the cabinet to prevent sagging with its consequent disadvantages.

Another object is to provide a simple and inexpensive device of this character which will not easily get out of order, and which will afford easy operation of the shelf and a firm support therefor.

The above objects are obtained by providing a pair of swinging arms pivoted to the cabinet or other supporting structure, the free ends of which are swung outwardly by the shelf as it is slid from the cabinet, and which arms act as supports for the outer portion of the shelf when it is drawn out of the supporting structure.

In the accompanying drawing:

Figure 1 is a plan view of a shelf provided with the supports.

Figure 2 is a sectional view taken on the line 2—2 of Figure 1.

Figure 3 is a broken plan view.

Figure 4 is a sectional view showing a detail of the pivot mounting.

Figure 5 is a perspective view showing the assembly of the shelf guide, the trackway and the mounting for the arm.

Figure 6 is an elevation partly in section showing a modification.

Describing the drawing more particularly, a supporting structure 7, such as a refrigerator or other cabinet, has mounted on the inner sides of its wall, a pair of U-shaped front brackets 8, each of which has a pair of vertically spaced legs 9 attached to the cabinet and a connecting portion 10 and a pair of rear brackets 11. Each pair, 8 and 11, of these brackets supports between them a guide 12, in which is slidably mounted a shelf 13.

In order to prevent the shelf from sagging when it is drawn out from the cabinet, and when the forward part thereof is beyond the forward ends of the guides 12, the following structure is provided. Each of the front brackets 8 has pivoted therein an arm 14, one end of which is upwardly bent to form a pivot pin 15 which extends up through openings in both legs 9 of the bracket 8 to a point above the shelf 13 and above the upper leg of the bracket 8 where it may be secured, as

by a nut 16. The opposite end of the arm 14 extends beneath the shelf and the end 17 thereof is upwardly bent and preferably rounded to afford a slideable bearing member.

To the underside of the shelf 13 is secured a 5 trackway 18 having a top wall 19 which bears upon the rounded ends 17 of the arms 14, and depending side walls 20 which serve to guide the ends 17 of the arms 14. The track 18 may advantageously be made in one piece, though a 10 separate section for each of the arms may be provided. The rearward ends of the track are located adjacent each side of the shelf 13 at a point approximately midway between the front and the back thereof and the track extends in a 15 curve forwardly and toward the center of the shelf. The rearward ends of the track 18 may be provided with walls 21 which act as stops. The upturned ends 17 of the arms 14 are engaged in the trackway and bear against the top wall 19 20 thereof, while the side walls 20 act to swing the ends 17 of the arms 14 as the shelf is drawn out or pushed in.

As the shelf is drawn outwardly the ends of the arms are swung out and slide along the track, and 25 the upturned ends bearing against the stop wall 19 afford a support for the shelf in advance of the cabinet, as shown more clearly in Figure 3.

In Figure 6 a modification is shown in which the arms 21 have rollers 22 journaled in their 30 ends. In this case the track 23 may be elliptical with a relatively narrow slot 24 in its bottom and in which a reduced neck 25 of the roller may travel.

The above described structure has many ad- 35 vantages. It is strong and supports the shelf firmly when extended. It produces very little friction and allows the shelf to be slid very easily. It is inexpensive to manufacture and attach and is of great assistance in providing for 40 the satisfactory use of sliding shelves.

From the foregoing it is thought that the construction, operation and many advantages of the herein described invention will be apparent to those skilled in the art without further descrip- 45 tion, and it will be understood that various changes in the size, shape, proportion and minor details of construction may be resorted to without departing from the spirit or sacrificing any of the advantages of the invention.

What I claim is:

1. In combination with a sliding shelf and a supporting structure therefor including a stationary wall, an arm pivoted to the stationary wall rearwardly of the front of the shelf and 55

having a free end, and a trackway secured to the shelf and slidably engaging the free end of the arm to cause the arm to be swung outwardly beneath the shelf as the shelf is slid out to afford

5 a support for the extended shelf.

2. In combination with a supporting structure and a shelf having openings therein slidably mounted thereon, an arm pivoted to the supporting structure near the front thereof and

10 beneath the shelf, said arm having a free upturned end, and a trackway having a continuous top wall mounted on the underside of the shelf and slidably engaging the free end of the arm, to cause it to swing outwardly beneath the shelf

15 as the latter is slid out, and the top wall of

the track resting on the upturned end of the arm to afford a support for the shelf.

3. In combination with a supporting structure and a shelf slidably mounted thereon, a bracket mounted on the supporting structure, an arm extending under the shelf and having an upturned end pivotally mounted in the bracket and extending upwardly above the shelf, the opposite end of the arm being free to swing beneath the shelf, and a means mounted on the underside of the shelf to cause the arm to swing outwardly as the shelf is slid out, to afford a support for the extended shelf.
